WELTING AND METHOD OF PRODUCING
WELTINGGeorge Hollis Jennings, Elmwood, East
Bridgewater, Mass.

Application May 29, 1933, Serial No. 673,413

8 Claims. (Cl. 12—146)

This invention relates to improvements in
welting and methods of producing welting.

More particularly it relates to calking welts and
the like, such as are used extensively for filling
the welt crease between the upper and the welt or
sole of a shoe, and which may be employed for
beading and finishing a joint between adjacent
surfaces in upholstery, and other articles of man-
ufacture.

10 The function of calk welting in a shoe is to fill
the angular crevice, at the above stated location,
so as to exclude mud, snow, water and dust. Also
it is desirable that the calk welting shall lend a
certain distinction and characterize to a shoe, by
15 presenting an attractive calking bead which may
be polished by the ordinary agencies for that
purpose.

In Goodyear welt shoes, the best kinds of calk
welting have a fin portion integral with the bead
20 portion, the fin being such that it can reach into
the welt crease, between the Goodyear welt and
the upper, to be pierced and held by the inseam
stitches which secure together the Goodyear welt
and the upper. The calking welt overlies the
25 main welt, its fin curving around the inner top
corner of the main welt, and ordinarily running
down across the inner vertical edge thereof, to a
place where the main welt, the bottom edge of
the upper, and a portion of the innersole, all rest
30 on the top of the outersole.

Calk welting intended for use in shoes of the
better quality is constructed on the theory that
the surface of its bead which will be exposed to
35 view, when in the shoe, should be grain surface.
The grain face is smoother, less porous and more
susceptible to taking a good polish than in a flesh
face. Also it is substantially more expensive.

Various prior proposals have been directed to-
ward getting the benefits and advantages of grain
40 leather at that area of the welting which is to be
exposed in a shoe, while employing the less ex-
pensive flesh surface at the areas which are not
to be exposed.

This invention has a similar primary object but
45 provides a distinctly new method for accomplishing
that object. Also it provides an improved
product.

By the method a prepared strip of leather having
50 a grain surface has its body subjected to a suc-
cession of transposing operations, whereby a part
of the body of leather including the flesh face is
turned, as on a hinge, in the midst of the leather
body, from its original relation to the part of the
55 body having the grain face, to a location more dis-
tant from that grain face. This, in a certain

sense, converts a portion of the width of the
leather strip into additional thickness of that
strip. The original strip, in a preferred form, ini-
tially has slightly greater width of grain sur-
face than is needed for providing the desired
5 grain surface of welting bead that is to fill the
crease from the top face of a Goodyear welt, for
example, to the adjacent upper. This slight sur-
plus may be cut away in a rectangular strip to a
depth approximating half the thickness of the 10
original strip, leaving a sort of L-shaped body.
The residue of thickness, that underlay the re-
moved strip, thus becomes a lateral projection of
flesh leather, which remains integral with and
alongside of that flesh leather which underlies the 15
intact grain surface. This lateral flesh leather,
which has the reduced thickness, is, according to
the invention, to be swung around 90° more or
less so that it will stand under the remaining grain
20 surface, adding itself in the direction which was
the original direction of thickness, to that body
of flesh leather which already is under that grain,
to make the fin part of the welt.

The invention provides for the accomplishing
of this by slitting the strip longitudinally at a 25
strategic location, which, preferably, will be at
the lower, inner angle of the hollow formed by
the said removal of material. And the slit is
shallow and oblique, preferably directed toward
the remote base angle of the strip which is di-
30agonally opposite the corner that was removed.
The adjacent flesh leather, under the grain sur-
face and beyond the slit, constitutes a hinge about
which the lateral body of flesh leather may be
bent rearward to make the fin, with the slit 35
spreading open. The transposition may be
executed in progressive stages by means of press-
ing or molding rollers which effect the bending
and swinging of, and mold the leather into the
40 new shape.

Preferably the remote base angle of the strip,
toward which the slit was directed, will be cham-
fered slightly prior to subjecting the strip to the
transposing pressure. The same said molding or
rolling may shape the grain surfaced portion of 45
the strip into the bead part of the welting with
a gently curved grain surface which is the part
to be exposed to view in the finished shoe.

Or, if desired, the original strip may approxi-
mate in width the full extent of bead surface 50
which is to be exposed in a shoe, in which case
all of the grain surface of that strip is to be left
intact, and there may be a removal of material
at a side edge, by grooving, with the slit at the
55 bottom of the groove.

It is intended that the patent shall cover, by suitable expression in the appended claims, whatever features of patentable novelty exists in the invention disclosed.

5 In the accompanying drawing:

Figure 1 is an isometric showing of a stock strip of leather from which my improved calk welting may be produced according to the method herein disclosed, indicating in dotted lines a corner strip

10 to be removed;

Figure 2 is an isometric showing of the same strip at an intermediate stage of my improved method;

15 Figures 3 and 4 show the same strip at subsequent stages of the method;

Figure 5 shows my improved welting in a preferred finished form;

Figure 6 is an elevation, in section, showing the welting of Figure 5 embodied in a shoe;

20 Figure 7 is an isometric showing of a narrower stock strip corresponding to Figure 1, which may be employed in practicing my improved method in a modified way;

Figure 8 shows an intermediate stage in the 25 conversion of the stock strip of Figure 7;

Figure 9 shows a modified form of finished 30 welting obtainable by my improved method from the strips of Figures 7 and 8; and

Figure 10 shows the welting of Figure 9 embodied in a shoe.

Referring to the drawing, two stock strips 10, 10' of leather are represented in Figures 1 and 7 respectively, each having a grain face, a flesh face and two edge faces. The strip 10 of Figure 1 has its grain face indicated at 12, its flesh face at 14 and its two edge faces at 16, 18, while the corresponding faces of the strip 10' are indicated by the numerals 12', 14', 16' and 18'.

40 According to my improved method the finished welting form is attained by transposition of leather under molding pressure. Preliminarily, however, the stock strip, whether 10 or 10', has a portion cut away to facilitate the desired transposition, and is slit longitudinally at a 45 strategic location to facilitate opening of the stock under the influence of the molding pressure.

50 In the case of stock strip 10, which has width of grain face a little greater than what is needed to surface a welting bead, the excess portion, as at 20, of that grain surface is removed, leaving intact the portion of grain which is for surfacing the welting bead. The portion 20 which is thus cut away may be a rectangular strip having depth 55 or thickness approximating half the thickness of the stock strip 10. And the removed strip 20 may be suitable for sale, or may be used in other connections.

60 As an illustrative example, a satisfactory commercial form of stock strip 10 may have width of grain face approximating $7/32$ of an inch, of which $5/64$ of an inch may be removed in the piece 20, leaving $9/64$ of an inch of grain for surfacing the welting bead. The thickness of the 65 stock strip ordinarily will approximate $5/32$ of an inch, of which $5/64$ of an inch may be removed in the piece 20.

70 The resulting strip, after cutting away the portion 20, will have an approximate L-shape, comprising a body in which the grain leather and flesh leather continue intact, and an integral lateral flange, projecting rectangularly from the intact body to the original edge 16 and composed entirely of flesh leather.

75 An important feature of the invention resides

in slitting the L-shaped strip strategically to facilitate the transforming of the strip by the subsequent molding operations. Such a slit is represented at 22 in Figures 1, 2. It is cut at the inner angle formed by removal of the strip 20, 5 preferably is directed diagonally toward the remote base angle 23 of the L-strip, needs to have but relatively little depth, and extends longitudinally through the length of the L-strip. Practically speaking $1/2$ of an inch of depth of slit has 10 been found satisfactory, although it may be made greater or less, in particular cases.

As a preliminary to the molding, I prefer also to cut away the square angle at 23, between flesh face 14 and edge face 18, to a rounded or chamfered form, as at 25 in Figure 2, which facilitates the swinging of the flange edge 16 to desired position in the finished welting strip. The rounding or chamfering at 25 may extend from about midway of the edge face 18, to about $1/3$ of the distance along flesh face 14.

The strip thus prepared, as seen in Figure 2, is ready for the transposing step, in which it is run between coacting rollers and is transformed and molded in shape by their pressure. Ordinarily this transformation will be effected in stages by a succession of applications of molding pressure by the rollers. The prepared strip is first suitably tempered and softened, which may include treatment with a solution of resinous material, as shellac, or with casein, or some other material that after drying and hardening will help hold the leather in its new form. Then it is run between pressure-molding rollers which spread the slit 22 open, swing rearward the lateral flange of leather which has the residue of edge 16, turning it on the adjacent strong mid-body of the leather, as a hinge, from its position of parallelism with to a position where it stands more or less perpendicular to the grain face, and is 40 more distant from the intact grain surface of the strip, its length being added to the thickness of that body of flesh leather which already stood back of the grain surface. As illustrated, it is not necessary that it go fully to perpendicularity. 45 This treatment by the transposing and molding pressure of the rollers may be repeated, if necessary, with increased pressure effective, until the shape of Figure 3 is attained. Then the curved back 24 may be skived off to produce the shape 50 seen in Figure 4, after which it may be subjected to a final compressing by the rollers to accomplish the finished welting form of Figure 5.

In the case of an initial stock strip like 10' of Figure 7, a somewhat similar procedure is followed. Here, however, a characteristic is that width of the stock strip approximates the desired finish width of surface of the welting bead. Consequently all of the grain leather is left intact, and the body of stock removed is taken from an 60 edge face 16', by cutting a groove therein as at 26. As illustrated in Figure 8, this groove 26 is of V-shape, starts from the edge of the grain surface, and has depth appreciably less than half the width of strip 10'. The slit 22' is at the bottom of this groove, having depth and direction as described for the slit 22 of Figures 1 and 2.

70 The transforming and molding of this modified form of prepared strip may be carried out in the same way as heretofore described, by means of compressing rollers. Preferably the strip will have been chamfered at 25' as in the previous case. And in either case a very small strip carrying the sharp angle at the juncture of grain face with edge face 18 or 18' may be skived off, if de- 75

sired. The finished welting produced from this modified stock strip, as seen in Figure 9, may have a narrower fin than has been usual heretofore; and may have a slightly curved shape, if desired, to facilitate embodiment of it in a shoe. The shorter fin may not reach down to the outersole as is usual, but it is securely held nevertheless by the inseam passing through what was a strong midportion of the original leather, as shown in Figure 10.

The increase of distance along the actual surface from grain face to flesh face, made by cutting away strip 20 in the one case, and by the groove 26 in the other case, furnishes an actual surface which is available for constituting one surface of the fin and which can reach further back from the grain face than would the original thickness of leather, without there having to be a mastication, crushing or other internal disruption of the leather in the molding process in order to make it reach back so far.

The bottom of the groove whether made by removal of substance from the edge at the location indicated in Figure 1, or that in Figure 7, lies near the mid-thickness of the leather strip; and the slit 22 or 22' cut therefrom into the remaining substance of the leather is therefore in that part of the leather which is strongest,—where the characteristic structure of the flesh face portion and that of the grain face portion intermingle. The leather substance about which the flesh portion turns as on a hinge when the slit is opened, and through which the stitches of the inseam will later pass, is therefore of the toughest and strongest character that was in the original strip.

Although illustrated in connection with a shoe of Goodyear welt type, the utility of the invention is not limited to shoes of that variety.

I claim as my invention:

1. The method of producing a welting strip having a bead and a fin, comprising the removing of part of the substance of the strip from one edge of a leather strip at a place at or near the face of the strip, thereby reducing the thickness of leather in the strip at that edge; and slitting the intact body of leather adjacent to the place where the said removal of substance occurred; followed by the eliminating of the slit by spreading it open, and, by pressure, molding the slit open to a shape wherein the material which constituted its walls becomes, on each side, approximately in alignment with the surface of that material which was left by the said removal of substance.

2. The method of producing a welting strip having a bead and a fin, comprising the cutting of a groove along an edge of a leather strip at or near one face corner thereof; the cutting of a slit further into the leather at the bottom of the groove, said slit extending into the leather which underlies the intact portion of said grooved face; followed by the bending of the residue on one side of said groove away from the residue on the other side of said groove, with a spreading open of the slit, and then, by molding pressure, ironing the leather stock on opposite sides of the opened slit simultaneously further open thereby to convert the slit walls into an extended surface for elongation of material to constitute a fin for the strip in welting form.

3. The method of producing a welting strip having a bead and a fin, comprising the cutting of a groove along an edge of a leather strip at or near one face corner thereof; the cutting of a

slit further into the leather from the bottom of the groove, said slit extending toward that remote corner of the strip which is diagonally opposite said groove; followed by the spreading of the residue of stock on one side of said groove away from the residue of stock on the other side of the groove, thereby eliminating the said slit by transposition of stock at each wall of the slit approximately into the same plane with the original surface stock which was adjacent to the mouth of the slit.

4. The method of producing a welting strip having a bead and a fin, comprising the cutting of a rabbet along an edge of the grain face of a leather strip having a grain face and a flesh face; the cutting of a diagonally directed slit at the bottom of the rabbet; followed by the bending of the strip open at the said slit by molding pressure, including a bending away from the grain face of that flesh face substance which is below the rabbet, on a hinge of the leather substance of the strip which lies adjacent to the bottom of said slit, and the setting of the bent strip, by molding pressure, into a bead and fin constituting a calk welting structure, the cross section of whose body substance, is free from lesion.

5. The method of producing a welting strip having a bead and a fin, comprising the removing of substance from one edge of a leather strip while leaving some substance of the strip at that edge; slitting the intact body of leather adjacent to the place where the said removal of leather occurred; chamfering away the corner of the strip between the other edge and that face of the strip at which substance was left; followed by the opening of the strip at said slit, with a molding of that said substance which was left into a welting fin, and a molding of the portion of the strip on the otherside of the slit into a welting bead integral with the fin.

6. The method of producing a welting strip having a bead and a fin, comprising the removing of substance from one edge of a leather strip while leaving some substance of the strip at that edge; slitting the intact body of leather adjacent to the place where the said removal of leather occurred; chamfering away the corner of the strip between the other edge and that face of the strip at which substance was left; followed by the opening of the strip at said slit, with a molding of that substance which was left and skiving that molded surface which includes the residue of said chamfer with adjacent edge and face.

7. Welting having a bead and a fin, comprising a leather strip in which the bead has a grain face, and the fin comprises, in large part, flesh leather, being leather stock which lay along the flesh face of the natural leather and comprises in part a portion of the mid-substance, being a backing of leather stock which lay along the said flesh face of the natural leather, in the midst between grain face and flesh face; said flesh leather and the backing of mid-substance being in a transposed position relative to the grain face of bead and standing more distant from said bead face than in the natural state; said transposition being from natural position through a substantial angle of bending to the fin position.

8. In a shoe having welt, upper and insole, and an inseam securing them together, the combination therewith, laid in the crease between welt and upper, of a leather calking welt having a grain leather bead exposed to view and having

an integral fin composed of mid-substance and flesh leather which together have been pressed away from the bead into laterally projecting relation thereto, said fin reaching in and secured by the inseam; in which combination the inseam passes through and only through that sub-

stance of the calking welt which in the original leather from which the calking welt was made constituted mid-substance of the leather, located between grain substance and flesh substance thereof.

GEORGE HOLLIS JENNINGS.
